INSECTICIDAL JET FOGGING UNIT

Robert Schmedes, Rochester, and John M. Nelson,
Webster, N.Y., assignors to Bernzomatic Corporation

Filed Sept. 12, 1969, Ser. No. 19,125

Term of patent 14 years

Int. Cl. D23—01

U.S. Cl. D23—18

FIG. 1.

FIG. 2.

FIG. 3.

FIG. 4.

FIG. 1 is a perspective view taken from the top, side and end of an insecticidal jet fogging unit showing our new design;

FIG. 2 is an elevational view taken from the end opposite that shown in FIG. 1 and showing an opening in the lower portion thereof;

FIG. 3 is an elevational view taken from the side opposite that shown in FIG. 1; and

FIG. 4 is a bottom plan view thereof.

I claim:

The ornamental design for an insecticidal jet fogging unit, as shown.
